ANTENNA EXCITATION SYSTEM

Robert Stephen Wehner, Hempstead, N. Y., assignor to Airborne Instruments Laboratory, Inc., Mineola, N. Y.

Application October 14, 1947, Serial No. 779,816

10 Claims. (Cl. 250—33)

1

This invention relates to antenna systems for the radiation and reception of radio waves. It relates more particularly to aircraft antennas and to methods and apparatus for feeding radio energy to such antennas.

The trend of development of modern aircraft has been toward increasingly higher flight speeds and, accordingly, toward more exacting airfoil design. At the same time the amount and complexity of electronic equipment carried in the plane for communication, navigation, collision warning, instrument landing etc., has increased.

In operation, much of this equipment requires the radiation or reception of radio waves and, accordingly, requires suitable antenna structures capable of efficient performance over the wide range of frequencies utilized by the electronic equipment. The increased flight speeds of the aircraft and the resulting necessity for careful aerodynamic design render undesirable the use of any externally projecting antenna structures that would alter the configurations of the aircraft surfaces.

It has become, therefore, of paramount importance to provide aircraft antenna systems which require no externally projecting or protruding portions. Many such "faired-in" or recessed antennas have been developed. These antennas, although operating satisfactorily for many applications in the superhigh frequency ranges, e. g. above 500 megacycles, generally have been unsuitable for operation in the lower frequency ranges. One reason for this unsatisfactory operation is that the radiating structures are necessarily larger for these lower frequency, i. e. longer wavelength, antennas than are those required for the higher frequency ranges, and it is, accordingly, more difficult to provide sufficiently large openings in the surface of the aircraft to permit the use of conventional cavity or slot type antennas.

Because of the large number of radio equipments which must be operated in the plane, and because of the large radiating structures required at these lower frequencies it is desirable that the faired-in antenna operate over a wide range of frequencies so that various electrical equipments may be connected as desired to the same antenna structure; and for many applications it would be desirable that no readjustment of antenna matching networks be required so that by the use of suitable band-pass filters several equipments could be connected simultaneously with the antenna.

As the frequency of operation is reduced the

5 flat surfaces of the aircraft suitable for ground surfaces, i. e. electrically conductive surfaces adjacent the antenna, become increasingly smaller electrically, and it is, therefore, essential that the antenna be constructed and driven (i. e. electrically energized) so that satisfactory operation may be achieved in conjunction with a relatively small ground plane, and that the effects of this ground plane be minimized so that the antenna impedance presented to the feed line is not altered excessively by frequency changes within the operating range.

10 The impedance presented to the antenna feed-line should be sufficiently high that ordinary coaxial line may be used to couple energy between the transmitting or receiving equipment and the antenna. If it is found necessary to employ impedance matching elements in conjunction with the antenna, it generally is desirable that such elements operate without readjustment over the entire frequency range with which the antenna is to be used. Such readjustment is inconvenient and precludes simultaneous use of the antenna with more than one electrical equipment.

15 20 25 In accordance with the preferred embodiment of the present invention a completely faired-in antenna is provided that is operable over a wide frequency range and which makes use of already existing aerodynamic surfaces as the radiating elements. This antenna provides vertically polarized radio waves, advantageous in this frequency range, and is capable of satisfactory operation in conjunction with an electrical- 30 35 40 45

ly small ground surface.

It is, accordingly, an object of this invention to provide an improved faired-in aircraft antenna system.

It is a further object of this invention to provide such an antenna system in which the effects of the ground plane configuration on the impedance characteristics of the antenna are minimized.

It is another object to provide such an antenna system utilizing a portion of the aircraft structure as a radiating element to provide vertically polarized radiation energy.

45 In one aspect of the invention it is an object to provide an improved wide band coupling system for aircraft antennas.

50 55 In another aspect of the invention it is an object to provide an improved broad band vertically polarized antenna system in which the driving impedance is maintained within practical operating limits of the characteristic impedance of a conventional type coaxial feed line over a wide

range of frequencies, or can be brought within these limits by an easily realizable non-adjustable impedance matching section.

The various features of novelty which characterize the present invention are pointed out with particularity in the claims annexed to and forming a part of this specification. For a better understanding of the invention, its advantages and the specific objects obtained with its use, reference should be had to the following descriptive matter and to the accompanying drawings, in which:

Fig. 1 shows the tail structure of an airplane with the position of the antenna excitation element indicated in broken lines;

Fig. 2 is an enlarged cross-sectional view of the tail fin and excitation element;

Fig. 3 is an enlarged cross-sectional view of the excitation element taken on line 3-3 of Fig. 2;

Fig. 4 is an enlarged cross-sectional view taken on line 4-4 of Fig. 2;

Fig. 5 shows the excitation element and the upper portion of the tail fin with the plastic tail cap removed;

Fig. 6 shows the upper portion of the tail fin with the plastic tail cap in place;

Figs. 7, 8 and 9 show the input impedance of one particular antenna structure and the change produced therein by simple matching sections;

Fig. 10 shows the standing wave ratio on the feedline of a typical antenna structure embodying the invention;

Figs. 11, 12 and 13 show typical field strength patterns of the radiating structure for the indicated radiation angles near the horizontal plane; and,

Fig. 14 shows a folded loop excitation element for operation over a narrower frequency range.

The characteristics of a given antenna are the same, if properly interpreted, regardless of whether that antenna is used for transmitting or receiving. This equivalence follows the reciprocity law which is an extension of the well-known reciprocity theorem found in electrical circuits. Although the discussion herein refers for the most part to transmitting antennas, the interpretation of the present disclosure is not to be so limited. The term radiating element, therefore, is to be construed, not as an element necessarily used for radiating, but rather one which is capable of radiating and, therefore, suitable for receiving. Other terms used herein, with relation to the radiation and reception of electro-magnetic energy, are to be similarly interpreted.

In order to provide a faired-in radiating element capable of satisfactory operation in the frequency range between 50 and 400 megacycles, a metal vertical stabilizer 2 (Fig. 1), or tail fin, of the aircraft may be utilized advantageously as the radiating element. One difficulty is that the ground surfaces formed by the horizontal stabilizers 4 and the adjacent portion of the fuselage 6 are small in terms of the wavelengths at which the dimensions of the tail fin make it most suitable as a radiator.

In order to minimize the effects of these ground surfaces, the tail fin 2 is excited or fed near the upper end. With such top feeding the impedance presented to the feed line, which is determined largely by the surface currents immediately adjacent the point of feed, does not change as rapidly with changes in frequency as if it were fed near the base where the small and discontinuous

ground surfaces would exert a controlling influence.

However, the dimensions and shape of the stabilizer are dictated ordinarily by aerodynamic considerations rather than electrical requirements. Thus, it is necessary to excite or drive the stabilizer as a radiating element without materially altering the outer surface configuration or weakening the structure.

In order that the vertical stabilizer 2 may be excited as a radiating element, the metal structure of the stabilizer is terminated along line 8. This structure is closed at the top by a metal plate 12 (Fig. 5) suitably secured to the upwardly extending sides of stabilizer 2. An excitation element 14, mounted above the stabilizer 2, is supported from plate 12 by insulating supports 16 and 18 constructed, for example, of impregnated Fiberglas.

To avoid changing the shape of the airfoil the excitation element 14 is shaped to conform generally with the desired surface configuration and covered with a housing 22 (Fig. 6) of plastic or other suitable insulating material, shaped to provide the desired aerodynamic characteristics.

To transfer energy from the transmitting or receiving equipment (not shown) to the excitation element 14, a coaxial cable 24 (Fig. 2) extends from this equipment upwardly through the interior of the vertical stabilizer 2 to the excitation element 14. The outer conductor of the coaxial cable 24 is grounded to the plate 12 and the inner conductor is connected to the excitation element 14.

The radio frequency energy delivered by the coaxial cable 24 to the excitation element 14 is coupled by capacity to the radiating surfaces of the vertical stabilizer 2. In order to reduce the direct, or shunt, capacity which is effectively between the inner conductor of cable 24 and the metal surfaces of stabilizer 2, a tapered section, generally indicated at 26, forms the lower part of element 14. The tip of this tapered section 26 joins the inner conductor of cable 24 near the surface of plate 12 and with gradually increasing dimensions upwardly, forms the excitation element.

The shape of element 14 is shown by Figs. 3, 4, and 5. The exact shape is not critical and again is governed to considerable extent by aerodynamic design considerations. It must, however, be sufficiently large to provide adequate series capacitive coupling between cable 24 and the surfaces of the vertical stabilizer 2, but in order that satisfactory operation may be had over a wide frequency range the dimensions of excitation element 14 are small in terms of wavelengths at the highest frequency of operation.

In order to avoid undesirable effects that might be caused by movement of the vertical rudder, the hinge line of which is indicated diagrammatically at 28 in Fig. 2, the excitation element 14 is placed well forward on plate 12 of the vertical stabilizer with a relatively flat surface 32 facing the rudder portion.

The antennas described above can be readily matched to a coaxial line having a 50 ohm characteristic impedance so that there is less than a two to one voltage standing wave ratio on the line over wide frequency ranges, provided, the height and cross sectional dimensions of the fin are sufficiently large as compared to a wavelength at the minimum frequency of operation, and that the ratio of the height of the excitation element to the over-all height in wavelengths is such as

to result in an input impedance of approximately 25 ohms or more over the desired frequency range. However, even when the ratio of excitation element height to the over-all height is as low as 0.10, which is considerably smaller than optimum, it is possible, by properly shaping and positioning the excitation element 14, to obtain input impedance characteristics which, if not naturally matched to the feed system over a broad band of frequencies, can be readily matched thereto by an easily realizable transforming section.

It has been observed that the vertical height of the stabilizer 2, the height of the excitation element 14, the length of the tapered portion 26, and the over-all height of the structure, are the more critical factors in determining the antenna impedance, whereas reasonable changes in the shape and other dimensions of the radiating element and in the excitation element 14 produce impedance changes of secondary importance.

Unexpectedly, the input impedance of this antenna is similar to that of a sleeve antenna with a comparable ratio of sleeve to over-all height and operating in conjunction with a large flat ground plane. This is particularly surprising because the combined area of the horizontal stabilizers and the upper adjacent surfaces of the fuselage are small in terms of square wavelengths and are far from continuous surfaces.

The useful operating range over which the antenna may be made to operate satisfactorily depends upon the height of the vertical stabilizer.

Best operation is obtained readily when the height of the vertical stabilizer is less than 0.4 or more than 0.6 wavelength. Advantageously, for wide band operation, the height of the stabilizer should be, therefore, at least 0.6 wavelength at the minimum frequency of operation, or it should be less than 0.4 wavelength at the maximum frequency of operation.

However, satisfactory but relatively narrow band antennas of this type may be constructed for operation in this intermediate range, i. e. where the stabilizer height is between 0.4 and 0.6 wavelength.

One particular antenna, constructed in accordance with the present invention and designed to operate over the frequency range from 100 to 250 megacycles, presents an input impedance over this frequency range as shown by line 32 in Fig. 7. As shown, the standing wave ratio on a 50 ohm coaxial transmission line was greater than two to one over most of the frequency range. However, the addition of a simple series condenser having a value of 19 μ uf. transforms the input of this antenna to that shown in Fig. 8. This impedance curve is further transformed to that shown in Fig. 9 by the addition of a 100 ohm series line section having a length of approximately 22 degrees at 100 megacycles. Thus, as shown in Figs. 9 and 10, the standing wave ratio on the 50 ohm line is less than two to one substantially throughout this frequency range.

Field patterns of this antenna at the mid-frequency of operation are shown in Figs. 11, 12 and 13. Fig. 11 shows the field pattern of the antenna 20 degrees below the horizontal plane; Fig. 12 indicates the pattern 10 degrees below the horizontal; and Fig. 13 shows the field pattern at an angle of 10 degrees above the horizontal plane.

It is apparent that the antenna may be constructed by insulating the top portion of the vertical stabilizer. This may be done by cutting

the metal stabilizer along a horizontal line and then connecting the surfaces and internal struts of the two stabilizer sections with insulating material having the requisite strength. Thus the top portion of the vertical stabilizer is separated by short lengths of insulating material from the lower portion. The top section is fed in the same manner as the excitation element 14 above.

Another type of excitation element is shown in Fig. 14, and has particular utility for applications in which the height of the plastic housing 22 is limited and where extremely wide band operation is not required. In this example, an excitation element 36 is formed by a strip of suitable conductive material, for example, $\frac{3}{8}$ inch diameter copper tubing having an over-all length substantially equal to one-half wavelength at the mid-frequency of operation. The inner conductor of the coaxial transmission line 24 is connected to one end of the excitation element 36 by a short tapered section 38; the opposite end of the copper tubing 36 is connected to the plate 12, as at 42, by screws or other suitable means.

In order to avoid adverse impedance changes which might be caused by movement of the metallic rudder portion of the stabilizer, the excitation element 36 forms a folded loop, as shown in Fig. 14. With this arrangement, that portion of the excitation element 36 nearest the rudder is a relatively low current area and, thus, minimizes impedance changes caused by coupling and hence dependent upon the angular position of the rudder.

In this specification and the accompanying drawings, there is shown and described a preferred embodiment and one modification of the invention; but it is to be understood that these are not intended to be exhaustive nor limiting of the invention, but on the contrary are given for purposes of illustration in order that others skilled in the art may fully understand the invention and the principles thereof and the manner of applying it in practical use so that they may modify and adapt it in various forms, each as may be best suited to the conditions of a particular use.

I claim:

1. A broadband vertically polarized aircraft antenna system, comprising a vertical tail fin having an outer conductive surface portion extending upwardly from the fuselage of said aircraft, an excitation element mounted above and supported by said conductive portion, a coaxial transmission line having an inner and an outer conductor and extending from the interior of said aircraft through said conductive portion to the upper portion thereof, a tapered section forming a part of said excitation element and electrically connected to the inner conductor of said coaxial line.

2. A vertically polarized top-fed antenna system, comprising a source of electrical energy, a ground plane, a radiator extending upwardly from said ground plane, a feedline connected to said source and extending to the upper end of said radiator, and an excitation element mounted above and feeding electromagnetic energy to said radiator one end of said element being connected to said feedline and the opposite end to the upper portion of said radiator and having a total length therebetween equal to an integral multiple of half wavelengths substantially at the mid-frequency of the operating range.

3. A vertically polarized top-fed antenna sys-

tem, comprising a ground plane, a radiator extending upwardly from said ground plane, an excitation element mounted above and feeding electromagnetic energy to said radiator and having a total length equal to one-half wave length substantially at the mid-frequency of the operating range, and a feedline connected to one end of said excitation element the opposite end of said element being connected to the upper surface of said radiator.

4. A coupling system for feeding electromagnetic energy to the structural portions of an aircraft to produce electromagnetic radiation therefrom, comprising a vertical tail fin of said aircraft having conductive and non-conductive portions, a source of electrical energy, a feedline extending between the base and the upper portion of said conductive portion, an excitation element mounted within said non-conductive portion and coupling electromagnetic energy between said feedline and said conductive portion, said excitation element comprising a conductor having a total length substantially equal to one-half wavelength at the frequency of operation, one end of said excitation element being connected to said feedline and the opposite end being connected to the upper surface of said conductive portion.

5. A vertically polarized top-fed antenna system, comprising a ground plane, a radiator extending upwardly from said ground plane, an excitation element mounted above and feeding electromagnetic energy to said radiator, said excitation element comprising a generally U-shaped length of conductive material, the midpoint thereof being displaced in the same horizontal direction from each end thereof and having an overall length substantially equal to one-half wavelength at the mid-frequency of the operating range, and a feedline connected to one end of said excitation element, the opposite end of said element being connected to the upper surface of said radiator.

6. A coupling system for feeding electromagnetic energy to the metal surface of the tail structure of an aircraft having a laterally movable vertical rudder, comprising a source of electrical energy, a stationary vertical tail structure having conductive and non-conductive surface portions, a feedline extending between said source of energy and the upper end of said conductive portion, and an excitation element mounted above and coupling electromagnetic energy between said feedline and said conductive portion, said excitation element comprising a length of conductive material having a total length substantially equal to one-half wavelength at the frequency of operation, one end thereof being connected to said feedline and the opposite end thereof being connected to the conductive portion of said tail structure, said element having areas of high and other areas of low current density therealong and having an area of low current density nearer said movable rudder than any area of maximum current density.

7. An antenna coupling system for use in the transmission and reception of radio waves in an aircraft of the type having an electrically conductive outer skin, comprising a vertical tail fin connected to and stationary with respect to the fuselage of said aircraft and having a first electrically conductive airfoil portion and a second

non-conductive airfoil portion, a feedline extending through said conductive portion, and an excitation element mounted in a fixed position on the upper surface of said conductive portion and confined within said non-conductive portion and connected to said feedline and coupling electromagnetic energy between said feedline and said conductive portion.

8. An antenna coupling system for feeding electromagnetic energy to an electrically conductive vertical structural element of an aircraft for radiation therefrom into surrounding space, said system comprising a vertical structural element forming an integral part of the surface of said aircraft and having a lower electrically conductive radiating surface portion and an upper non-conductive surface portion, an excitation element mounted within said non-conductive portion and coupling electromagnetic energy to said conductive portion, a tapered portion connected to said excitation element, and a feedline connected to said tapered portion of said excitation element and extending through said conductive portion.

9. An aircraft antenna system comprising a vertical airfoil having an exposed electrically conductive portion and an exposed insulating portion, the outer end of said conductive portion being closed by and electrically continuous with a conductive plate capped by said insulating portion, a feedline having first and second conductors and extending from the interior of said aircraft to said plate, said first conductor being connected to said plate, and an excitation element mounted within said insulating portion and comprising a loop of conductive material extending between said second conductor and said plate.

10. A broadband vertically polarized aircraft antenna system, comprising a vertical stabilizer extending outwardly from the fuselage of said aircraft and having an outer exposed conductive surface portion electrically continuous with the outer surface of said aircraft fuselage, an excitation element supported by the outermost portion of said conductive portion and extending beyond said conductive portion a distance equal to at least 0.10 of the total height of said stabilizer, impedance matching means connected to said excitation element and positioned outside said conductive portion, a feedline extending between said impedance matching means and the interior of said aircraft, and a streamlined non-conductive housing surrounding at least part of said excitation element and supported by said conductive portion.
